UNITED STATES PATENT OFFICE.

BENSON F. WADDELL, OF NEW YORK, N. Y.

DESIGN FOR A DIAPHRAGM FOR A RADIO LOUD SPEAKER.

Application filed August 2, 1927. Serial No. 22,980. Term of patent 14 years.

To all whom it may concern:

Be it known that I, BENSON F. WADDELL, a citizen of the United States, residing in the borough of Queens, county of Queens, city and State of New York, have invented a new, original, and ornamental Design for Diaphragm for a Radio Loud Speaker, of which the following is a specification, reference being had to the accompanying drawing, forming part thereof.

Figure 1 is a view showing in front elevation a diaphragm embodying my design; and

Figure 2 is a view in side elevation of Figure 1.

I claim:

The ornamental design for a diaphragm for a radio loud speaker, as shown.

BENSON F. WADDELL.
